(57) **CLAIM**

The ornamental design for a colony counter, as shown.

DESCRIPTION

FIG. 1 is a perspective view of the colony counter;
FIG. 2 is a right side elevation view of the colony counter
of FIG. 1, the side opposite being a mirror image;
FIG. 3 is a top view of the colony counter of FIG. 1;
FIG. 4 is a bottom view of the colony counter of FIG. 1;
FIG. 5 is a front elevation view of the colony counter of FIG.
1; and,
FIG. 6 is a rear elevation view of the colony counter of FIG.
1.

The broken line showing is included for the purpose of
illustrating non-claimed subject matter and forms no part of
the claimed design.
